(57) **CLAIM**

The ornamental design for a personal videoconferencing device, as shown and described.

DESCRIPTION

FIG. 1 is a perspective view showing the front and right side of a personal videoconferencing device, wherein the device is shown in an upwardly tilted orientation;

FIG. 2 is a left side view of the personal videoconferencing device of FIG. 1, wherein the device is shown in a non-tilted orientation;

FIG. 3 is a right side view of the personal videoconferencing device of FIG. 1, wherein the device is shown in a non-tilted orientation;

FIG. 4 is a front elevational view of the personal videoconferencing device of FIG. 1, wherein the device is shown in a non-tilted orientation;

FIG. 5 is a rear elevational view of the personal videoconferencing device of FIG. 1, wherein the device is shown in a non-tilted orientation;

FIG. 6 is a top plan view of the personal videoconferencing device of FIG. 1; and,

FIG. 7 is a bottom plan view of the personal videoconferencing device of FIG. 1.

The broken lines shown in FIGS. 1-7 are for illustrative purposes only and form no part of the claimed design.
